(No Model.)

N. WILSON.

MACHINE FOR RESTORING INSULATED WIRE.

No. 601,694.

Patented Apr. 5, 1898.

Fig. 1

Fig. 2

UNITED STATES PATENT OFFICE.

NELSON WILSON, OF PORTLAND, OREGON, ASSIGNOR OF ONE-THIRD TO
CHARLES BOLEN, OF SAME PLACE.

MACHINE FOR RESTORING INSULATED WIRE.

SPECIFICATION forming part of Letters Patent No. 601,694, dated April 5, 1898.

Application filed August 20, 1897. Serial No. 648,929. (No model.)

To all whom it may concern:

Be it known that I, NELSON WILSON, of Portland, in the county of Multnomah and State of Oregon, have invented a new and Improved Machine for Restoring Insulated Wire, of which the following is a full, clear, and exact description.

The invention relates to insulated wire used for electrical purposes; and its object is to provide a new and improved machine for restoring injured insulated wire by straightening the old wire, removing the insulation therefrom, and reinsulating the wire to permit its reuse the same as new wire.

The machine consists principally of a winding device for winding up the straightened and newly-insulated wire and imparting a traveling motion to the wire under treatment, a straightening device for straightening the old insulated wire, a stripping device for removing the insulation from the wire, and a covering or winding device for winding the insulating fabric upon the stripped and straightened wire.

The invention further consists of various parts and details and combinations of the same, as will be fully described hereinafter and then pointed out in the claims.

Reference is to be had to the accompanying drawings, forming a part of this specification, in which similar characters of reference indicate corresponding parts in both the figures.

Figure 1 is a side elevation of the machine, with parts in section; and Fig. 2 is a plan view of the same.

The improved machine is mounted on a suitably-constructed frame A, on one end of which is journaled a drum B, containing the old wire C to be restored into newly-insulated wire C', adapted to wind up on a drum D, journaled on the other end of the frame A. On the shaft of the drum D are secured fast and loose pulleys E, connected with other machinery for imparting a rotary motion to the said drum to wind up the new wire and to impart a traveling motion to the wire under treatment to cause the same to unwind from the drum B. The wire C, after leaving the drum B, is passed one or more times around a drum F, secured on a shaft F', journaled in suitable bearings on the main frame

A, the said shaft being connected by beveled gear-wheels F² and G' with a longitudinally-extending shaft G, rotated by the said gear-wheels from the shaft F', receiving its rotary motion by the traveling wire passing around the drum F. The shaft G serves to drive a spool-carrier H for winding the insulating fabric upon the wire, as hereinafter more fully described.

After the wire C leaves the drum F it passes between vertically-disposed straightening-rolls I I' I² and I³ I⁴, of which the rolls I I' I² are journaled on a stationary frame J, while the other rolls I³ I⁴ are journaled on a frame J', laterally adjustable by means of a screw J² and nuts J³. By this arrangement the wire passing between the sets of rolls is straightened, and the adjustment of the rolls I³ I⁴ causes the wire to pass the rolls at such an angle that any short turns in the wire will be removed.

The straightened wire C² after it leaves the straightening-rolls passes between stripping-knives K K' for removing the old insulation from the wire. The knives K K' extend vertically and have their cutting edges curved, as plainly indicated in Fig. 1, to readily strip the old insulation off the wire as the latter passes between the two knives. The knives K K' are attached to base-plates K² K³, held laterally adjustable on arms L L', respectively, by means of bolts K⁴, screwing in the said arms and engaging lateral slots in the said base-plates. (See Fig. 2.)

The arms L L' are supported on studs L² L³, secured on brackets N N', attached to the main frame A, the studs permitting of turning the base-plates K² K³, and with the same the knives K K' to bring their upper cutting edges in the desired angular relation to the wire, so as to insure a proper stripping off of the insulation.

The straightened and stripped wire C³ after leaving the knives K K' passes through a revolute arbor O, journaled in suitable bearings P, attached to the main frame A. The arbor O is provided with a gear-wheel O' in mesh with a gear-wheel O², secured on the shaft G, previously mentioned, and driven from the drum F by the traveling wire, as above explained.

On the forward end of the arbor O is secured the spool-carrier H, carrying a spool H', from which unwinds an insulating material C⁴, passing around a finger H², likewise held on the said carrier H. The material C⁴ then passes to the wire after the same has left the forward end of the arbor O, and as the carrier H is revolved the material C⁴ is wrapped upon the wire C⁸ in front of the rollers Q Q', engaging the material on opposite sides, as will be readily understood by reference to the drawings. The newly-covered wire C' unwinds from the rollers Q Q' upon the drum D to be wound up.

Now by the arrangement described the speed of the wire as it is wound up on the drum D regulates the speed of the winding or covering device for placing the insulating material on the wire, so that the same number of turns of the insulating material is given to each foot of wire, thus insuring a uniform covering of the wire.

The machine is very simple and durable in construction and enables electric companies to restore their old injured insulated wire in the manner above described.

Having thus fully described my invention, I claim as new and desire to secure by Letters Patent—

1. A machine for restoring insulated wire, provided with a straightening device for straightening the old insulated wire, and a stripping device in advance of the said straightening device for removing the insulation from the wire, substantially as shown and described.

2. A machine for restoring insulated wire, comprising a winding-up device, for winding the straightened and new insulated wire, and imparting a traveling motion to the wire under treatment, a straightening device for straightening the old, insulated wire, a stripping device for removing the insulation from the wire, and a covering or wrapping device for winding new insulating fabric upon the stripped and straightened wire previous to winding up the new wire on the said winding device for winding up the finished wire, substantially as shown and described.

3. A machine for restoring insulated wire, comprising a straightening device for straight-

ening the injured insulated wire, a stripping device forward of the said straightening device, for removing the old insulation from the straightened wire, and a covering or wrapping device in advance of the said stripping device, for placing a new insulating material on the straightened and stripped wire, substantially as shown and described.

4. A machine for restoring insulated wire, comprising sets of rolls between which the injured insulated wire passes to straighten the same, a pair of knives between which the straightened wire passes, to remove the old insulation therefrom, an arbor through which travels the stripped, straightened wire, and a spool-carrier on the said revoluble arbor, for winding a new insulating material upon the said wire, substantially as shown and described.

5. A machine for restoring insulated wire, comprising sets of rolls between which the injured insulated wire passes to straighten the same, a pair of knives between which the straightened wire passes, to remove the old insulation therefrom, an arbor through which travels the stripped, straightened wire, a spool-carrier on the said revoluble arbor, for winding a new insulating material upon the said wire, means for imparting a traveling motion to the wire, to pass the same through the said rolls, the knives and the arbor, and a drum driven from the said traveling wire, and connected with the said carrier, to rotate the same, substantially as shown and described.

6. A machine for restoring insulated wire, provided with a pair of knives having curved cutting edges between which passes the wire, the knives being laterally adjustable, substantially as shown and described.

7. A machine for restoring insulated wire, provided with a pair of knives having curved cutting edges between which passes the wire, the knives being laterally adjustable, and means for setting the knives at a desired angle at their cutting edges relatively to the wire passing between the knives, substantially as shown and described.

NELSON WILSON.
